MOVABLE MULTIPLE MAGAZINE UNIT FOR
TYPESETTING MACHINES

Charles J. Romyns, Lynbrook, N. Y.

Application March 14, 1947, Serial No. 734,696

2 Claims. (Cl. 199—45)

1

This invention relates to a movable multiple magazine unit for typesetting machines, and the primary purpose of the invention is to provide a unit that will carry more magazines in the typesetting machine than are carried on the present type of machines, thus giving the operator of the machine more variety of type without having to take off magazines and replacing them with others carrying different kinds of type.

The present typesetting machines carry only four main magazines, and four auxiliary magazines, giving the operator thereof only ten faces of type.

An object of the invention, therefore, is to provide a typesetting machine giving a greater variety of type faces, in that the unit on the machine carries thirty-two faces of type of varying sizes which are available to the operator, without the removal or insertion of any magazines. However, if more than thirty-two faces are required, a rather unusual requirement, the magazines can be easily and simply removed from the unit as are the magazines on the present day typesetting machines.

The unit comprising the invention can be built into the present typesetting machine with very little change in the matrice assembling or the distributing mechanism.

With the above and other objects and advantages in view, the invention consists of the novel details of construction, arrangement and combination of parts more fully hereinafter described, claimed and illustrated in the accompanying drawings in which:

Figure 1 is a perspective view, partly broken away, of a standard typesetting machine having an embodiment of the invention secured thereto;

Figure 2 is a side elevational view partly in section, of the machine and attachment embodying the invention;

Figure 3 is a plan view of a magazine for a single distribution;

Figure 4 is a sectional view on the line 4—4 of Figure 3;

Figure 5 is a sectional view on the line 5—5 of Figure 3 of a single distributing magazine;

Figure 6 is a plan view of magazines in pairs for multiple distribution and

Figure 7 is a sectional view of multiple distributing magazines with the type feeding channel associated therewith.

Referring more in detail to the drawings, the reference numeral 10 designates a standard typesetting machine to which the front support or arm 11 of the invention is secured by bolts 12.

2

The support 11 is provided with a bearing end 13, in which is journaled the shaft 14 having the crank 15 on the outer end thereof for the rotation of the shaft.

5 Mounted on the shaft 14, and spaced from each other by the spacing member 16, are the front and rear discs 17 and 18 respectively, and distributor bracket 19 journals the opposite end of the shaft 14. The discs rotate with the shaft 14 when the crank 15 is turned, and bolts 20 pass through the discs 17 and 18 to retain the discs in fixed alinement with each other when the nuts 20' on the bolts are tightened.

The discs are provided with a circular row of 15 apertures 21, which are concentric with the shaft 14, and are adapted to receive the stop pin or stud 22 which is slidably mounted in the extension 23 on the bearing 13 of the arm 11. This pin prevents rotation of the discs when the device 20 is in use, and withdrawal of the pin from the apertures by means of the pivotal lever 41 will permit rotation of the discs as desired. The lever 41 is provided with a forked end 42 to engage the grooved head 43 of the stud 22, and the lever is pivoted on the extension 23 as shown in Figure 1, so that movement of the lever will withdraw or insert the stud as desired.

The discs are provided with radially extending 30 slots 24 which are in alinement with each other, and type magazines 25 are positioned in the slots as shown in Figure 1. The slots 24 are provided along one longitudinal edge with a recess 26 in which the lugs on the magazine 25 are received, to properly align the magazines in the slots, and 35 magazine locks 27 on the magazines retain the magazines in fixed relation to the discs.

Mounted on the bracket 19 is the distributor bar 29, distributor screws 30 and channel entrance 31 which will align itself with the magazine 25 by means of the upper stationary part 32 of the magazine, as shown in Figure 5, whereby matrices are delivered to the magazines.

In Figure 6, the discs 16 and 18 are provided with radially extending pairs 33 of slots 24, to hold the magazines 25, and in this instance, the discs are used in mixed type machines.

In Figure 7, the stationary parts 32 of the magazine are aligned with the upper and lower channels 34 and 35 respectively, which co-act with the 50 upper and lower distributor bars 36 and 37 and the upper and lower distributor screws 38 and 39 respectively.

The shaft 24 rotates on roller bearings and ball thrust bearings 40, which assures easy turning thereof by the operator.

The invention comprises the circular frame which is mounted for rotation on a standard typesetting machine, and when one magazine is used, two faces of type are accessible to the operator, and when two magazines are used, as on the multiple type unit, four faces of type are accessible to the operator. The frame is made for single or multiple distribution, and by the rotation of the crank 15, the magazines carrying type faces can be presented for use in the machine 10.

Safety devices now used on typesetting machines can be used on the unit embodying the invention, and the operation of the device is similar to the present typesetting machines, except that more type faces are available for use.

The unit is simple to operate, and efficient and durable in use, being applied to a standard typesetting machine with little change in the machine.

From the foregoing description, it is believed that the construction and operation of the invention will be apparent to those skilled in the art, and it is to be understood that changes in the minor details of construction, arrangement and combination of parts may be resorted to, provided they fall within the spirit of the invention and the scope of the appended claims.

Having thus described the invention, what is claimed as new and desired to be secured by Letters Patent is:

1. In a typographical machine, the combination of a base support, an arm extending upwardly therefrom, a bearing portion on said arm having a bearing surface lying in a plane at an angle to the vertical axis of said arm, a bearing opening in said bearing portion normal to said bearing surface, a shaft journalled in said opening and having one end extending beyond said bearing portion, a hand crank fixed on said extending portion of said shaft, a first and second disc on said shaft, a spacing member on said shaft and between said discs for spacing the same, a journal adjacent said second disc for supporting an end

of said shaft, means extending axially of said shaft securing said discs against said spacing member, thrust bearings between said first disc and the bearing surface of said bearing portion, locking means between said bearing arm and said first disc for indexing and locking the same in selected positions, a plurality of circumferentially-spaced radially extending slots in said discs, corresponding slots of said discs being in alignment with each other, and a type magazine removably mounted in each pair of corresponding slots of said discs whereby each magazine extends substantially parallel to said shaft.

2. In a typographical machine, the combination of a base support, an arm extending upwardly therefrom, a bearing portion on said arm having a bearing opening, a shaft journalled in said opening and having one end extending beyond said bearing portion, a hand crank fixed on said shaft, a pair of discs on said shaft, means securing the same in spaced relationship on said shaft, locking means between said bearing arm and said first disc for indexing and locking the same in selected positions, a plurality of circumferentially-spaced radially extending slots in said discs, corresponding slots of said discs being in alignment with each other, and a type magazine removably mounted in each pair of corresponding slots of said discs whereby each magazine extends substantially parallel to said shaft.

CHARLES J. ROMYNS.
